UNITED STATES PATENT OFFICE.

BENJAMIN F. LOLLISS, OF BURWYN, ILLINOIS, ASSIGNOR OF ONE-HALF TO OTTO S. FLATH, OF CHICAGO, ILLINOIS.

SWITCH AND SIGNAL ROD OR PIPE-CARRIER SUPPORT.

Application filed April 17, 1922. Serial No. 554,342.

My invention relates more particularly to the elements for supporting the pipe carriers which are usually employed in distant switch or signal operation; and the invention has for 5 its object the provision of a construction not only possessing the requisite strength, adapted to resist the thrusts that result from movement of the operating elements or pipe lines in opposite directions, but which will be comparatively cheap in manufacture and which may be readily assembled and put into place on the supporting piers or foundations on 10 which devices of this character are usually placed.

15 The invention contemplates the provision of a support which will be simple in construction and wherein the respective elements are so formed and correlated as to permit ready access to any of the elements, while at the 20 same time the elements will be so associated as to reinforce one another and vibration or movement of the fastening elements prevented; the invention contemplating a pipe carrier top or support which may be employed 25 with or without a pedestal when occasion requires.

The advantages of my invention will be more fully comprehended from the detailed description of the accompanying drawings, 30 wherein:—

Figure 1 is a perspective view illustrating a modified form of my invention, with the respective elements associated and assembled in place and disclosing a pair of pipe carriers.

35 Figure 2 is a cross sectional view taken substantially on the line 5—5 of Figure 1 looking in the direction of the arrows.

Figure 3 is a detail perspective view of one of the spacer elements employed with the construction illustrated in Figure 1.

The tops or supports for the carriers are usually mounted on and secured to a concrete pier or foundation which is indicated at 10. The rod or pipe support comprises the pedestals 11, of which any suitable number are employed commensurate with the width of the foundation or pier. The pedestals are usually of suitable metal having a main body portion preferably provided with depending lugs or 45 feet as at 12 adapted to rest on the pier or foundation; while the upper surface is of sufficient width and length to provide proper support for the other elements. My improved pedestal has its opposite sides or ends on the 50 top surface provided with upstanding lugs or

shoulders as at 13, 13 whereby to properly hold the longitudinally disposed supports or bars later to be described. One side of the pedestal is provided with an ear or lobe as at 14 preferably disposed at equal distances from 60 the opposite ends of the pedestal and at a point between the top and lower surfaces thereof and this lobe or ear is apertured as at 15 to receive a suitable bolt or rod 16 whereby to secure or clamp the pedestal to the pier or 65 foundation. The rod or bolt is preferably of the construction shown in Figure 1, having the lower hook end disposed in a suitable socket in the concrete pier or foundation, while the upper threaded end is disposed through the lobe or ear 14 to receive a suitable nut.

70 The supporting element consists of a pair of Z-bars 32 arranged with the intermediate portions of the bars disposed vertically so as 75 to have one side or leg of each bar extend flush with the upper surface of the pedestal 11 while the upstanding or intermediate portion of the Z-bar is arranged in abutting relation with the upstanding shoulders 13 at 80 opposite ends of the pedestals, with the result that the other longitudinal side or leg of the Z-bar will be disposed horizontally and in overlapping relation with the ends of the pedestals, as more clearly shown in Figure 2. 85

The last mentioned side or leg of each Z-bar is apertured or slotted at predetermined distances apart to receive the bolts 29 whereby to secure the carriers 21 in place on the supporting element. The apertures or slots are 90 arranged equi-distances apart corresponding to the distances between the feet or base portions 20 of the correlated carrier members 21, which are identical in construction and arranged in pairs to provide suitable bearing 95 for the grooved roller 22 which is provided with a suitable trunnion as at 23 adapted to be disposed in the transversely disposed slot 24 of each carrier member 21. The upper ends of the respective carrier members are 100 shown bifurcated at 25 to receive the trunnion of a second roller 26 which is held against displacement by any suitable means as for example by the cotter pins 27; the second or upper roller 26 being intended to maintain the rod or pipe, indicated at 28, in proper position in the groove of the lower roller 22.

105 With this construction I prefer to employ a suitable number of spacing members 33, preferably one at each side of the founda- 110

tion or pier, namely at a point immediately above the pedestals 11. These spacing members 33, which are preferably in the nature of small channels as shown in detail in Figure 3, are apertured at 34 to receive the upper end of the clamping bolt or rod 16 secured to the pier or foundation and disposed through the lobe or ear 14 of the pedestal. With this construction, it is evident that when the nuts 10 on the upper ends of the clamping bolts or rods 16 are firmly screwed into place, the pedestal will not only be secured to the pier or foundation, but the spacing members 33 will also be clamped down in firm relation with the lower horizontally disposed sides or legs of the Z-bars, thereby firmly securing the Z-bars on the pedestals. The spacing members 33 will prevent any movement of the Z-bars toward each other, while the upstanding flanges 13 of the pedestals will prevent any possibility of separation of the Z-bars or supporting members.

As is apparent from the construction shown in Figure 1, this split channel type of support, namely the separate Z-bars, are adapted for use with or without a pedestal, as the Z-bars may be placed directly on the pier or foundation and secured thereto through the medium of the spacing elements or plates 33 and the bolts or rods 16, as the plates 33 will firmly hold the Z-bars in place.

To permit longitudinal adjustment of the supporting member the two Z-bars may be slid longitudinally for adjustment before 35 fastening the nuts on the upper ends of the hook-bolts into firm clamping relation with the spacing and clamping plates 33.

The bolt-receiving holes may either be punched or slotted; while the upstanding flanges at the ends of the pedestals will hold the supporting element against lateral movement, namely in a direction lengthwise of the pedestals; at the same time the right angularly formed longitudinal sides of the Z-bars 45 32 are of width sufficient to receive either the head or the nuts of the bolts whereby the

carriers are fastened into place, so that the nuts or bolt-heads will be in abutting relation with the vertically disposed portion of the sides of the supporting elements and will thus 50 prevent accidental turning of the bolts or nuts through the vibration to which the pipe carrier supports are subjected during operation.

With the construction shown, it is evident 55 that the supports may be employed in situations where there are slight differences in height of the various correlated piers or foundations; that is to say, the construction permits installation without the use of pedestals 60 on all of the piers or foundations if there is any difference in height. These supporting members or elements are preferably of sheet metal and may be formed by stamping, through the use of dies or otherwise, whereby 65 uniformity throughout and interchangeability may be obtained.

I have shown what I believe to be the best adaptation of my invention and have described the same in terms employed merely 70 as terms of description and not as terms of limitation, as structural modifications are possible and may be made without, however, departing from the spirit of my invention.

What I claim is:—

In combination with a foundation or pier, supporting means comprising a pair of long bars Z-shape in cross section, the lower horizontal sides of both bars being disposed laterally toward each other while the upper horizontal sides of both bars extend outwardly, an apertured spacing and clamping plate arranged intermediate of the Z-shape bars in lapping relation with the lower horizontal sides of both bars and in abutting relation 85 with the vertically disposed intermediate portions of said bars, and a hook bolt passing through the aperture in said plate and engaging with the foundation or pier whereby said pair of bars are secured in place.

BENJAMIN F. LOLLISS.
